Attorney.

UNITED STATES PATENT OFFICE.

WILLIAM MILLS, OF BIRMINGHAM, ENGLAND.

FOLDING SEAT-STICK.

1,241,753.

Specification of Letters Patent.

Patented Oct. 2, 1917.

Application filed August 9, 1915. Serial No. 44,550.

To all whom it may concern:

Be it known that I, WILLIAM MILLS, a subject of the Kingdom of Great Britain, residing at Atlas Aluminium Works, Grove 5 street, Birmingham, in the county of Warwick, England, engineer, have invented certain new and useful Improvements in Folding Seat-Sticks, of which the following is a specification.

10 This invention relates to that type of folding seat stick in which a flexible strap forming the seat is supported by double arms which are pivoted to the head of the stick, in such a manner as to either close 15 up together when not in use, or unfold when in use, the present improvements mainly consisting of so arranging the arms that the center of the flexible support when in use finds a bearing on the joint part of the 20 head of the stick.

By means of this improvement the flexible strap is caused to accommodate the contours of the sitter's anatomy instead of drawing the two arms together and thereby 25 causing an uncomfortable nipping of the occupant's seat.

In order that this invention may be clearly understood and readily carried into practice, reference may be had to the appended explanatory sheet of drawings, upon 30 which:—

Figure 1 is a part-sectional elevation of a folding seat stick according to the present invention showing the seat in the open position.

Fig. 2 is a plan with part broken away of the seat stick shown in Fig. 1.

Fig. 3 is a part elevation of the seat stick shown in Figs. 1 and 2, with the parts in 40 the folded or collapsed condition.

Fig. 4 is a part-elevation of the seat stick shown in Figs. 1, 2 and 3, the aspect of elevation being at right angles to that in the case of Fig. 3.

45 In a convenient embodiment of this invention, the head or top of the stick is provided with a joint piece α to which projection lugs b on the arms c are pivoted, preferably by means of separate pins c^1 which 50 are each passed through each of the lugs to each arm and through the joint piece, and riveted at each end.

Alternatively, a separate pivot screw may be passed through a perforation in each lug 55 and screwed into the side, a shoulder being provided upon the shank of the screw to

limit the inward screwing and to permit of the screw being tightly screwed up.

The arms are so shaped as to accommodate a joint piece α of substantial width between the lugs, so as to form a substantial bearing for the flexible strap d when in use. 60

In elevation the arms c are curved to form downward recesses e so as to form a recess at each side of the center to accommodate the seat of the occupant, and the flexible strap d is attached to cross bars f arranged at the point near the upper part of the curve of the arms c , such flexible strap d being so arranged that when sat 70 upon it finds a bearing at the center upon the central joint piece α . At their inner extremities the arms are furnished with elongated transverse struts g , and the latter are adapted to engage with the sides of the 75 support α and limit the downward movement of the arm c . Such struts g also limit the upward movement of the arms in such a manner that when the arms are folded or collapsed they are retained in alinement 80 with the stick.

On plan the arms c are slightly curved inward at h for avoiding extreme pressure on the underside of the thigh, and are then gradually curved out again to the point 85 where the cross bars f are provided, to which the ends of the flexible strap d are attached, the sides of such arms being then curved around to form a bow i at each end, which bows act as a handle when the seat is 90 closed up.

For the purpose of retaining the arms in the folded condition by a semi-locking connection, the locking and unlocking of which takes place automatically upon the ordinary 95 closing or opening of the arms, the outer extremity or bow-part i of one arm is centrally provided with a short projection i^1 , the head of which may be enlarged, and which projection is adapted to engage with 100 in a socket i^2 provided in the adjacent face of the other arm. This socket i^2 may or may not have a reduced neck, or it may be arranged at an incline and may have a shoulder at its one side. 105

A spring engagement between the projection and socket is provided for, this spring engagement being conveniently arranged for by placing the projection and socket slightly out of center, so that in order 110 for the projection to enter the socket, one or both of the arms has to be constrained,

this resulting in the necessary friction to retain the arms together through the medium of the connection.

The projection may, for instance, be placed a little higher than the socket, that is to say, a little farther away from the axes of articulation in a radial direction. As a result of this, it is necessary to the bow-part *i* of the arm or arms to be slightly displaced 10 in order to enable the projection to enter the socket.

An intermediate strut or bar *j* may be arranged at that part of the arm narrowed by the aforementioned curves *h*, one of the said bars *j* being used if desired for providing a projecting stud *k* upon which the disk *l* for the foot of the stick can be fixed when not in use, and as the curves of the arms when closed form a curved projection at 20 this point, as shown in Fig. 3, the arrangement permits of the placing of the bottom half of the disk *l* in the user's pocket for supporting the stick when not required to be carried by the hand.

25 The means permitting of the assemblage of the disk *l* upon the stud *k* may be of any suitable or convenient form.

The bar *f* to which the strap *d* is fixed is preferably of such form that the top part 30 of the bar is slightly above the sides of the arms so that the strap is at each end raised a little above the sides of the arm, this assisting in preventing the under portion of the thigh from bearing against the sides 35 of the arms. The strap is preferably attached by being wrapped partially around the bar *f* where it is secured on the inside either by riveting to the bar, or by being sewn.

40 It is, of course, to be understood that instead of allowing the strap *d* to find its bearing on the center joint itself, any convenient additional supporting means may be provided at this point.

45 Spring washers *m* may be provided on the pivots *c* between the lugs *b* and the joint piece *a* so as to provide an even frictional action in the closing and opening of the supporting arms, such spring washers consisting of a disk of spring steel of wavy formation or of other form adapted to impart 50 the desired resilience.

Copies of this patent may be obtained for five cents each, by addressing the "Commissioner of Patents, Washington, D. C."

Instead of providing for the attachment of the disk *l* to a projecting stud such as *k*, said disk *l* may, when the arms are folded 55 as shown in Fig. 3, be disposed between the arms.

What I claim as my invention, and desire to secure by Letters Patent is:—

1. A seat stick comprising a rod, a pair 60 of downwardly bowed arms pivoted at their inner ends to the head of the rod and a strap, whose ends are connected adjacent the extremities of the arms, extending so closely above the head of the rod as to bear 65 thereon when in use whereby the strap accommodates the contour of the body.

2. A seat stick comprising a rod, a pair 70 of downwardly bowed arms pivoted at their inner ends to the head of the rod, such arms being further curved inwardly toward their inner ends, and a strap, whose ends are connected adjacent the extremities of the arms, extending so closely above the head of the rod, as to bear thereon when in use, whereby 75 the strap accommodates the contour of the body.

3. A seat stick comprising a rod, a pair 80 of yoke shaped arms pivoted at their inner ends to the head of the rod, cross bars provided upon such arms adjacent their extremities, such bars being mounted above the arms and a seat strap whose ends are connected to the bars, such strap extending so closely above the head of the rod as to 85 bear thereon when in use whereby said strap accommodates the contour of the body.

4. A seat stick comprising a rod, a pair 90 of arms being pivoted to the head of same at their inner ends, locking means provided at the outer ends of the arms, comprising a male member secured to the outer end of one of the arms and a female member secured to the outer end of the second arm, spring engagement between the two being 95 effected by means of positioning them slightly out of center.

In witness whereof I have hereunto set my hand in the presence of two witnesses.

WILLIAM MILLS.
